Specification for Design.

Patented June 24, 1913.

Application filed December 6, 1912. Serial No. 735,336. Term of patent 14 years.

To all whom it may concern:

Be it known that I, ELLSWORTH A. HAWTHORNE, a citizen of the United States, and a resident of Bridgeport, county of Fairfield, State of Connecticut, (whose post-office address is 35 Spruce street, Bridgeport, Connecticut,) have invented a new, original, and ornamental Design for Lamps, (Case B,) of which the following description, in connection with the accompanying drawings, is a specification.

In the drawings, Figure 1 shows a side elevation of a lamp having the design of my

invention, and Fig. 2 shows a front elevation of the same.

What I claim is.

The ornamental design for a lamp, as shown.

In testimony whereof, I have signed my name to this specification, in the presence of two subscribing witnesses.

ELLSWORTH A. HAWTHORNE.
